DESIGN FOR A LOOSE LEAF BINDER PLATE

Ferdinand Bodenhofer, New York, N. Y.

Application April 9, 1936, Serial No. 62,033

Term of patent 14 years

To all whom it may concern:

Be it known that I, Ferdinand Bodenhofer, a citizen of the United States and a resident of the city of New York (Borough of the Bronx), county of the Bronx, and State of New York, have invented a new, original, and ornamental Design for a Loose Leaf Binder Plate, of which the following is a specification, reference being had to the accompanying drawing, forming part thereof, in which

Figure 1 shows a top plan view of a binder plate embodying my new design;

Figure 2 shows a side elevation.

Figure 3 is a cross section taken on the line 3—3 in Figure 1.

I claim:

The ornamental design for a loose leaf binder plate, substantially as shown.

FERDINAND BODENHOFER.
